[57] **ABSTRACT**

The application describes an electronic organ in which a rhythmic production of various chords and/or individual notes is triggered whenever an individual key is depressed. This mode of operation is achieved by use of a rhythm producer, a tone generator, and appropriate switching and control apparatus.

ELECTRONIC ORGAN

BACKGROUND OF THE INVENTION

This invention relates to an electronic organ and more particularly relates to an electronic organ wherein the depression of at least one key, preferably in the low range of the key board, results in a rhythmically broken-up note.

In electronic organs, it is conventional to supply an accompaniment (i.e., a rhythmic sequence of notes) with the left hand and by means of a pedal. With this arrangement, a predetermined note is associated with each key of the manual and pedal keyboards. To perform the accompaniment, appropriate keys must be depressed with the left hand with a frequency and sequence corresponding to the desired rhythm. A similar technique must be used on appropriate pedals. For these reasons, the accompaniment makes high demands on the skill and concentration of the player.

For simplifying the accompaniment, certain keys of a manual may be arranged to produce not only individual notes, but also predetermined chords, so that the keys associated with the individual notes of the chords need not be simultaneously depressed. However, this arrangement facilitates playing to only a small extent, since the player must still play each note and pedal in the proper rhythm. Thus, even with these auxiliary means, heavy demands are made on the player's manual dexterity and sense of rhythm.

Another known electronic organ frees the player from the necessity of playing keys in the proper rhythm by employing a rhythm-providing means which automatically breaks up the accompanying notes into a predetermined rhythm pattern. Thus, as long as a key is depressed, the appropriate note is rhythmically broken up. However, the manual and pedal keys associated with desired chords must still be selected by the player. As a rule this involves the playing of a plurality of keys one after the other for the same chord (i.e., alternating basses and bass melodies). Therefore, the player must possess good musical knowledge, considerable skill, excellent technique, and the ability to concentrate. This is a difficult task since he must also play the melody with his right hand.

There are also known automatic electronic percussion instruments which automatically produce, in adjustable rhythm patterns, sounds which imitate conventional percussion type instruments. With this arrangement, no provision is made for a change in pitch or scales.

Accordingly, it would be desirable to have an electronic organ which obviates the disadvantages of the known electronic organs and which almost completely relieves the player of the work of providing the accompaniment.

SUMMARY OF THE INVENTION

According to a principal feature of the invention, rhythm means are provided to effect a rhythmic production of various chords, individual notes and/or individual notes and chords in predetermined sequence whenever an appropriate key is depressed. If only one key is held, this rhythm means enables the production of a plurality of notes or chords, one after the other, in accordance with a predetermined rhythm.

According to another feature of the invention, the keys producing the rhythmic note sequences are provided with a plurality of contacts which, upon depression of a key, connect the note generators associated with the particular notes or chords of the desired rhythmic note sequence to control means. The control means are connected between the contacts and the output of the electronic organ and are controlled by the rhythm means which enables the control means to conduct note generator signals in accordance with the desired rhythm pattern.

By following the teaching of the present invention, the player is relieved of almost the entire work involved in the accompaniment. As a result, a rich and full accompaniment may be supplied by inexperienced players having little musical knowledge or skill. If the player depresses a key producing the accompaniment, there is produced a predetermined sequence consisting of chords, individual notes, alternating basses and bass melodies (which may also be built up from the chords) at the instants of time corresponding to the desired rhythm. These instants of time may be determined by the rhythm means which, in predetermined sequence, supplies switching pulses to the control means.

Of course, it is also possible to utilize an electronic percussion instrument which is then co-controlled by the rhythm means of the present invention. For example, the percussion instrument can be actuated when a new rhythm commences. However, it can also be controlled by the switching-in of the other notes of the accompaniment scale (i.e., by other switching pulses of the rhythm means).

DESCRIPTION OF THE DRAWINGS

These and other advantages and features of the present invention will hereafter appear for purposes of illustration, but not of limitation, in connection with the accompanying drawings wherein like numbers refer to like parts throughout, and wherein:

FIG. 1 is a schematic front elevational view of an electronic organ incorporating a preferred embodiment of the present invention; and

FIG. 2 is a schematic diagram of a characteristic portion of a switching circuit of an electronic organ made according to the invention.

DESCRIPTION OF THE PREFERRED EMBODIMENT

FIG. 1 shows an electronic organ 1 which stands on legs and comprises a lower portion 2 which has a loudspeaker 3. A manual 5 is disposed in an upper portion 4 of the organ. The left-hand side of the upper portion has keys 6 which produce an accompaniment according to the invention. Arranged over the keys 6 are switching means 7 by which the rhythm may be altered (i.e., for example from a waltz to a foxtrot). Furthermore, by means of some of the switches 7, supplementary key contacts may be switched in so that, upon depressing one of the keys 6, not only the rhythmic note sequences, but also the notes associated with keys 6 become audible. In addition to switching means 7, there are also provided the conventional register or stop switches 8, 9 and, where appropriate, loudspeaker regulators (not shown).

FIG. 2 shows the characteristic elements of a preferred circuit for the production of rhythm according to the invention. A sound generator 10 produces tone signals corresponding to all the sounds necessary for the production of rhythm and the formation of notes. Exemplary notes produced by the generator are indicated by letters superimposed on generator 10. In this regard, plain lower case letters indicate notes in the region of middle C, lower case letters bearing the exponent 2 indicate notes an octave above the plain lower case letter notes, plain upper case letters indicate notes an octave below the plain lower case letter notes, and underlined upper case letters indicate notes two octaves below the plain lower case letter notes. Electrical devices capable of operating as generator 10 are well-known to those skilled in the electronic organ art.

Two of the keys 6 are indicated by broken lines 11 and 12, and all the contacts of a key are simultaneously closed by depressing the key. For example, when playing key 11, a contact 13 is closed, so that the a.c. voltages associated with the notes c^2 , a^2 and f^2 are fed, via resistors 14, 15 and 16, a contact 13, a connecting lead 17, a control stage 18 and a resistor 19, to a sound forming means 20, in which the appropriate sound is "mixed." The a.c. voltage mixture thus produced appears across the output 21 of the sound forming means and, if appropriate after amplification, is fed to a loudspeaker, such as amplifier and loudspeaker 21A.

In a corresponding manner, a.c. voltages associated with the notes c , a and f are fed via resistors 22, 23 and 24, a contact 25, a connecting lead 26, control stage 27, and a resistor 28, to the sound-forming means 20. An a.c. voltage associated with the note C is fed, via the resistor 29, a contact 30, a connecting lead 31, a control stage 32, a resistor 33 and a resistor 34, to the sound-forming means 20. An a.c. voltage corresponding to the note F is fed, via a resistor 35, a contact 36, a connecting lead 37, a control stage 38, a resistor 39 and resistor 34, to the sound-forming means 20. Simultaneously, the said a.c. voltage passes from the resistor 39, via voltage divider 40 having the divider ratio 1:2 and serving for the formation of a subharmonic, and a resistor 41, into the sound-forming means 20. Normally, control stages 18, 27, 32 and 38 are switched so that lines 17, 26, 31 and 37 are not connected to sound-forming means 20.

To the control stages 18, 27, 32 and 38 there are fed, via conductors 42, 43, 44 and 45, control pulses derived from a rhythm provider 46 and which, on appearing, on every occasion, switch the control stages 18, 27, 32 and 38 into a conductive condition (if so required with a predetermined adjustment time), so that the conductors 17, 26, 31 and 37 are connected with the sound-forming means 20. Upon disappearance of the control pulses from the rhythm provider 46, the passage through the control stages 18, 27, 32 and 38 is once again interrupted, if necessary, after a predetermined time corresponding to naturally occurring build-up and decay times. Apparatus, such as relays or transistor switches, capable of operating as control stages 18, 27, 32 and 38 are well-known to those skilled in the art.

According to the invention, the opening and closing of the control stages 18, 27, 32 or 38 is effected with a predetermined rhythm and in a predetermined

sequence, depending on the rhythm desired. For example, in the case of a waltz rhythm, rhythm signals in the form of pulses from the rhythm provider 46 may appear on the leads 42 to 45, in the following sequence: 42, 45, 45, 42, 45, 45, 42, 45, 45, etc. In the case of a foxtrot, the sequence may for example be: 42, 45, 43, 45, 42, 45, etc. or 42, 44, 42, 45, 42, 44, etc.

Naturally, it is also possible to achieve a correspondingly more complicated tone or note formation. This will not require any special discussion here, since it results entirely of its own accord from the individual rhythm formation and the corresponding interpretation of the rhythm provider 46. Rhythm providers of the type described are well-known in the electronic organ art.

Associated additionally with key 11 is a contact 47 which directly connects a note associated with key 11 to the sound former 20. In this way, when key 11 is depressed, a corresponding continuous note is produced. Additional switches may be provided which directly connect all notes associated with a key to the sound-forming means 20, so that the notes sound continuously as long as the key is depressed.

Key 12 has contacts 48, 49, 50 and 51 which are connected to the collecting leads 17, 26, 31, 37 in the same manner as the contacts of key 11. When key 12 is depressed, these contacts pass a.c. voltages corresponding to notes produced by sound generator 10, via resistors 52-59, to the control stages 18, 27, 32 and 38. Associated with key 12 are other notes (i.e., C and G) and also other chords c , e , g and also c^2 , e^2 , g^2 . A contact 60 of key 12 produces a note which sounds continuously when a key is depressed. This note may, together with the corresponding notes of other keys, belong to a normal scale, so that, with the aid of these contacts, it becomes possible to play a bass melody by actuating the accompanying keys.

In FIG. 2, only two keys 11 and 12 are indicated, but the number of keys may be any desired number. If desired, all the keys of a manual, a supplementary keyboard or a pedal board may be used.

When key 11 is depressed, the F major triad is heard in the higher notes due to the closure of contact 13, the F major chord is heard in the lower notes due to the closure of contact 25, the alternating bass C is heard due to the closure of contact 30, and the lower bass F is heard due to closure of the contact 36.

In a corresponding manner, when key 12 is depressed, the C major triad is heard in the higher notes due to the closure of contact 48, the C major chord is heard in the lower notes due to closure of contact 49, the alternating bass G is heard due to closure of contact 50, and the low bass C is heard due to closure of contact 51.

When key 11 is depressed, it may be that a note will not immediately be produced. The note may not sound until the rhythm provider 46 supplies a switch-through pulse to one or the other of the control stages 18, 27, 32 or 38. In this way, the corresponding a.c. voltages are switched through in correspondence with the rhythm adjusted at the rhythm provider 46. This arrangement is especially advantageous when the player fails to release key 11 soon enough. Even though the note is held, no sound will be generated until the rhythm provider produces the next note in the rhythm

sequence. If key 11 is released too soon, the only result will be that some notes or chords will "drop out" of the rhythm. However, the rhythm itself will not be fundamentally influenced. Thus, even though the rhythmic tone sequence is relatively complicated, the rhythm always remains relatively uninfluenced by the manner in which the player depresses the accompaniment keys.

Obviously, it is quite readily possible to effect the switching-over of the rhythmic tone sequence from major to minor harmonies and other types of chords. For this purpose, there may be provided special harmony switches (not shown here) with the aid of which tones, triads or chords corresponding to these harmonies may be connected to the keys 11, 12 etc. Naturally, it is also possible to "assemble" the bass notes and other notes at will and to program the switching-in thereof in the rhythm provider 46.

Those skilled in the art will recognize that the embodiment disclosed herein may be altered and modified without departing from the spirit and scope of the invention as defined in the accompanying claims.

What is claimed is:

1. In an electronic organ comprising a first key and a second key and a sound-forming means for mixing tone signals and producing notes, apparatus for causing the notes to sound in a predetermined rhythmic pattern comprising:

generator means for transmitting a first tone signal corresponding to a first note over a first conducting path, for transmitting a second tone signal corresponding to a second note over a second conducting path, for transmitting a third tone signal corresponding to a third note over a third conducting path, for transmitting a fourth tone signal corresponding to a fourth note over a fourth conducting path, for transmitting a fifth tone signal corresponding to a fifth note over a fifth conducting path, and for transmitting a sixth tone signal corresponding to a sixth note over a sixth conducting path, said first, second, and third notes forming the notes of a first harmonic chord, and said fourth, fifth, and sixth notes forming the notes of a second harmonic chord different from the first harmonic chord;

rhythm means for generating at least first, second, and third rhythm signals having a predetermined rhythmic pattern;

first control means for conducting a tone signal to the sound-forming means in response to the first rhythm signal;

second control means for conducting a tone signal to the sound-forming means in response to the second rhythm signal;

third control means for conducting a tone signal to the sound-forming means in response to the third rhythm signal;

first switch means connected in the first conducting path responsive to depression of the first key for conducting the first tone signal to the first control means;

second switch means connected in the second path responsive to depression of the first key for conducting the second tone signal to the second control means;

third switch means connected in the third conducting path responsive to depression of the first key for conducting the third tone signal to the third control means;

fourth switch means connected in the fourth conducting path responsive to depression of the second key for conducting the fourth tone signal to the first control means;

fifth switch means connected in the fifth conducting path responsive to depression of the second key for conducting the fifth tone signal to the second control means; and

sixth switch means connected in the sixth conducting path responsive to depression of the second key for conducting the sixth tone signal to the third control means, whereby the first, second, and third notes may be sounded as the first harmonic chord in the predetermined rhythmic pattern in response to depression of only the first key and whereby the fourth, fifth, and sixth notes may be sounded as the second harmonic chord in the predetermined rhythmic pattern in response to depression of only the second key.

2. In an electronic organ comprising a first key and a second key and a sound-forming means for mixing tone signals and producing notes, apparatus for causing the notes to sound in a predetermined rhythmic pattern comprising:

generator means for transmitting a first tone signal corresponding to a first note over a first conducting path, for transmitting a second tone signal corresponding to a second note over the first conducting path, for transmitting a third tone signal corresponding to a third note over the first conducting path, for transmitting a fourth tone signal corresponding to a fourth note over a second conducting path, for transmitting a fifth tone signal corresponding to a fifth note over a third conducting path, for transmitting a sixth tone signal corresponding to a sixth note over a fourth conducting path, for transmitting a seventh tone signal corresponding to a seventh note over the fourth conducting path, for transmitting an eighth tone signal corresponding to an eighth note over the fourth conducting path, for transmitting a ninth tone signal corresponding to a ninth note over a fifth conducting path, and for transmitting a tenth tone signal corresponding to a tenth note over a sixth conducting path, said first, second, third, fourth and fifth notes forming the notes of a first harmonic chord, and said sixth, seventh, eighth, ninth and tenth notes forming the notes of a second harmonic chord;

rhythm means for generating at least first, second and third rhythm signals having a predetermined rhythmic pattern;

first control means for conducting a tone signal to the sound-forming means in response to the first rhythm signal;

second control means for conducting a tone signal to the sound-forming means in response to the second rhythm signal;

third control means for conducting a tone signal to the sound-forming means in response to the third rhythm signal;

first switch means connected in the first conducting path responsive to depression of the first key for conducting the first, second and third tone signals to the first control means; 5
 second switch means connected in the second conducting path responsive to depression of the first key for conducting the fourth tone signal to the second control means;
 third switch means connected in the third conducting path responsive to depression of the first key for conducting the fifth tone signal to the third control means; 10
 fourth switch means connected in the fourth conducting path responsive to depression of the second key for conducting the sixth, seventh and eighth tone signals to the first control means; 15
 fifth switch means connected in the fifth conducting path responsive to depression of the second key for conducting the ninth tone signal to the second control means; and

20

sixth switch means connected in the sixth conducting path responsive to depression of the second key for conducting the tenth tone signal to the third control means, whereby the first through fifth notes may be sounded as the first harmonic chord in the predetermined rhythmic pattern in response to depression of only the first key, and whereby the sixth through tenth notes may be sounded as the second harmonic chord in the predetermined rhythmic pattern in response to depression of only the second key.

3. Apparatus, as claimed in claim 2, and further comprising seventh switch means responsive to the depression of the first key for directly conducting a seventh tone signal to said sound-forming means, whereby said seventh tone signal is conducted continuously and said first through sixth tone signals are conducted according to said rhythmic pattern.
